ELECTRONIC MULTIPLYING DEVICE

Justin S. Compton, Lebanon, and Lawrence D. Kilheffer, Dayton, Ohio, assignors to The National Cash Register Company, Dayton, Ohio, a corporation of Maryland

Application October 18, 1945, Serial No. 622,978

50 Claims. (Cl. 235—61)

1

This invention relates to a multiplying machine the digit-representing elements of which are electron tubes which are actuated by electric impulses, and particularly pertains to a multiplying machine in which multiplication is achieved by successive addition and by simultaneous entry of product data into one or more denominations of an accumulator during a given stage of operation.

The machine operates at extremely high speed because it has no moving mass during an operation except those associated with electrons and other electric charges.

The chief units of the machine are an impulse generator including multiplicand control keys, a multiplier unit including multiplier control keys, a denominational accumulator, a denominational distributor for relaying and routing impulses from the impulse generator to the pertinent denominations of the accumulator, and a stage control device for correlating the operation of the multiplier unit and the denominational distributor unit.

The accumulator consists of a plurality of denominational rings of digit-representing gaseous discharge tubes, said rings being arranged in an ascending order of powers. Each ring has a tube for each denominational digit, including zero. The tubes of a ring are rendered conducting one at a time in sequence by impulses received over a denominational input conductor. Between each two denominations, a transfer tube is provided to cause a transfer of a carryover impulse when the lower denominational ring of the two operates through zero, said transfer being delayed until the responsible multiplicand entry has been completed. Such delayed transfer prevents interference between impulse-generator-produced data and transfer data. Each denomination of the accumulator is connected by its input conductor to an associated output conductor of the denominational distributor unit.

The denominational distributor unit consists of a number of self-extinguishing gas discharge relay electron tubes arranged in a square of rows and columns, there being a row for each denomination of multiplicand keys in the impulse generator unit, and a column for each denomination of keys in the multiplier unit. Output conductors from the denominational distributor are provided for each diagonal line of tubes in the square, and these output conductors are connected to the accumulator input conductors so that impulses generated to represent data

2

in a given denomination of the accumulator will be routed there.

The impulse generator consists of nine gaseous discharge electron tubes connected in an operative chain series so as to fire automatically one after the other from the beginning tube of the series when a firing impulse is given it. As each generator tube fires, it produces an impulse which is available to each of a plurality of denomination-representing output conductors, each of said conductors being controlled by a corresponding set of nine multiplicand digit keys. By operation of a selected key in selected denominations, the multiplicand factor is set up. Each of these impulse generator output conductors is coupled to all the tubes in a corresponding row of the denominational distributor and receives, for each operation of the set of impulse generator tubes, a number of impulses equal to the value of the operated key in that denominational bank.

The stage control unit has in it a number of gaseous discharge tubes equal to the number of columns in the denominational distributor, which number is the same as the number of denominational banks of keys in the multiplier unit. The stage control tubes are rendered conducting in sequence, and conduction in one of the control tubes primes the corresponding column of tubes in the denominational distributor, which priming action persists until that stage of the multiplying operation is completed by the multiplier unit. When a column of tubes in the denominational distributor is primed, the advent of an impulse from the impulse generator to any one of those tubes in the primed column fires the tube and relays and impulse on the corresponding diagonal output conductor.

The multiplier unit consists of nine gaseous discharge tubes, which are selectively controlled successively by each of a plurality of multiplier denominational key banks, each of such banks representing a stage of operation. Selective operation of digit keys in the multiplier unit determines how many of the multiplier tubes will fire in a given stage. Each firing of a multiplier tube gives rise to an impulse which fires the impulse generator tubes to give them a complete cycle of serial operation. Depending on what key, if any, is depressed in a denomination of the multiplier unit, a corresponding number of the multiplier tubes will fire successively in that stage, each firing resulting in a complete operation cycle of the impulse generator.

A control tube is fired automatically at the

end of a cycle of the impulse generator to cause transfers to be made in the accumulator by causing the functioning of a row of transfer control tubes. At an end of an operation of the transfer control tubes, an impulse is directed to the multiplier unit to fire the next tube in the cycle of the stage in operation. At the completion of a particular stage operation of the multiplier unit, a tube is automatically fired to shift the stage control to another stage control tube, which also commences a new stage operation under control of the next higher key bank of the multiplier unit. Means is provided for by-passing any multiplier key bank in which a key has not been depressed.

On the last multiplier-induced cycle of the impulse generator, the multiplication is completed.

Although the device is disclosed for use in the decimal system, any denominational base may be used. Any number of key banks can be used in either the multiplier unit or the impulse generator unit, provided the number of stage control tubes and denominational distributor tubes is correspondingly increased. The number of denominational banks in the accumulator may be increased indefinitely without regard to the remainder of the device. As a transfer operation for any denomination occurs in about one ten-thousandth of a second, any delay caused by increasing the number of banks in the accumulator and thus increasing the delay between cycles of the impulse generator is inconsiderable from a practical viewpoint.

The time taken for a multiplication operation is a function of the speed of tube operation and circuit conditions. Specific values will be given for circuit elements. The gas discharge tubes chosen as preferred are of the 2C4 or 6D4 type having an argon gas content and a grid, in addition to the anode and the cathode, the grid being positioned to cause a tube to fire when the grid is about 12 volts negative with respect to the cathode when the anode-cathode potential is about 120 volts. Under the specified values of circuit elements, the time taken for a multiplication of 999 by 999 will consume less than one-half second. Increase in the number of multiplicand denominations will not increase the time of impulse generator operation, because all multiplicand output conductors receive the generated impulses simultaneously. Increase in the number of denominations in the multiplier will increase the maximum time of operation by about 0.1 of a second for each added denomination, plus increased time for transfers, which depends on the necessary increased size of the accumulator.

Although the speed of the disclosed device is fast for commercial purposes, it may be increased, if desired, by increasing the firing speeds of the tubes, it being possible to increase the speed by a factor of from ten to a hundred, depending on tubes and circuit elements now available.

The chief advantage of the disclosed device, over other types of electronic multiplying devices using successive addition of unit-representing impulses, is the elimination of all but nine digit tubes in the multiplier unit and also in the impulse generator unit, making the device expandable in digit capacity without increase in the number of multiplier and multiplicand tubes. Another advantage of this device over what is known in electronic multiplying devices is the saving of time by simultaneous entry of data in more than one denomination of the accumulator during a given entry operation.

It will be obvious that the device can be used for simple adding by multiplying the number to be added by one.

Therefore, it is an object of this invention to provide an electronic multiplying machine operating on the principle of successive addition and having means for entering data into more than one denomination of an accumulator at the same time.

Another object of the invention is to provide an electronic multiplying machine requiring, for the multiplier factor and also for the multiplicand factor, a set of tubes equal in number to the digits in a denomination of the numerical system used, no matter how many denominational places in either factor.

Another object of the invention is to provide an electronic accumulator of a plurality of denominational orders with means to delay transfers of carryover data until after the completion of a period of data entering.

Another object of the invention is to provide an electronic multiplying machine wherein the multiplicand factor is entered repeatedly into the accumulator, and carryover data is caused to be transferred between successive entries.

Another object of the invention is to provide such an electronic multiplying machine in which the end of a transfer operation initiates the next multiplicand entry.

Another object of the invention is to provide an electronic multiplying machine having data-entering cycles and transfer cycles, the end of one type of cycle initiating the other type of cycle until completion of the multiplying operation.

Another object of the invention is to provide a multiplying device employing electron tubes as digit elements and operating on the principle of successive cycles of addition of the multiplicand factor in each of a plurality of stages under control of a multiplier factor unit, said addition data of a cycle being entered in the appropriate denominations simultaneously, and any necessary transfers of carryover data occurring between addition cycles.

With these and other objects in view which will make themselves apparent, the novel device will be disclosed with reference to the drawings, which are in no way to be deemed to limit the scope of the invention as otherwise specified and claimed.

Fig. 8 shows the tens of thousands and hundreds of thousands banks of the accumulator.

The multiplicand unit

Referring to Fig. 2, the Multiplicand unit includes nine digit-representing grid-controlled gaseous discharge electron tubes, numbered 1, 2, 3, 4, 5, 6, 7, 8, and 9, arranged in a potential-supply and operative network so that, if a tube of

lower value is fired and rendered conducting, the remainder of the tubes of higher value will be automatically rendered conducting one at a time in sequence, ending with the tube representing "9." If a positive electric impulse is impressed on terminal 100, it will cause the "1" tube 101 to become conducting, which in turn causes the "2" tube 102 to become conducting, and so on until the "9" tube 103 is rendered conducting, after which the "Transfer Initiator" tube 104 is rendered conducting. Each of these conducting tubes almost immediately becomes extinguished in a manner to be explained. As each digit tube or the tube 104 fires, its cathode becomes more positive in potential, due to a resistance in each cathode supply circuit, and such rise in potential is used as a positive potential impulse impressed on an associated output conductor, such as conductor 105 associated with the "1" tube. The positive impulse of the "Transfer Initiator" tube 104 is impressed on conductor 106.

Each impulse output conductor, like conductor 105, is connected through a rectifier like rectifier 107 to a terminal point like point 108, said rectifier being oriented to pass positive potential impulses originating at the associated cathode toward the point 108 but not in a reverse direction. Points like points 108 and 109, connected to the cathode of the "2" tube through rectifier 110, are connected by a rectifier like rectifier 111 oriented to pass positive potential impulses from point 108 toward point 112 but not in a reverse direction. Rectifiers like rectifiers 107 and 110 are provided to prevent dissipation of produced impulses among the nine cathode supply systems.

Anode potential is supplied to the tubes of Fig. 2 from a 115-volt positive source 113 through resistor 114 of 250 ohms, point 115, resistor 116 of 500 ohms, and point 117. Point 115 is coupled to ground through .5-microfarad stabilizing capacitor 118. The anode of "Transfer Initiator" tube 104 is connected to point 117 directly, and the anodes of the digit-representing tubes are connected to point 117 through 3,500-ohm resistor 119.

The cathode of the "Transfer Initiator" tube 104 is coupled to ground through 50,000-ohm resistor 120 in parallel with .001-microfarad capacitor 121. Each of the cathodes of the digit-representing tubes is coupled, as shown with regard to the "9" tube 103, on one side to ground through a 15,000-ohm resistor like resistor 122 in parallel with a .001-microfarad capacitor, like capacitor 123, and on the other side to negative 150-volt conductor 124 through a 150,000-ohm resistance, like resistor 125, a point like point 126, and a 300,000-ohm resistance like resistor 127.

The control grid of each tube except the "1" tube 101 is biased by connection to the cathode supply network of the previous tube of the series. Thus the "Transfer Initiator" tube grid 128 is connected through 500,000-ohm resistor 129 and point 130 to point 126. In a similar manner, grid 131 of the "9" tube is connected through 500,000-ohm resistor 132 and point 133 to point 134 in the cathode supply circuit of the "8" tube 135.

Each digit tube grid, excepting the grid of the "1" tube, is coupled through a point, like point 133 of the "9" tube grid supply, to negative potential supply conductor 124 through a .001-microfarad timing capacitor like capacitor 136. "Transfer Initiator" tube grid 128 is connected through point 130 and .001-microfarad capacitor 137 to ground. These capacitors are for timing only, preventing the too rapid firing of the tubes in

sequence. Obviously, the "1" tube 101 needs no such timing device because it is the first tube to fire.

The grid of the "1" tube is biased by being connected through resistor 138 of 500,000 ohms to point 139, which is connected on one side through 50,000-ohm resistor 140 to ground and on the other side through 250,000-ohm resistor 141 to negative supply conductor 124.

Under the circumstances given, the cathode of "1" tube 101 is normally at about 5 volts negative with respect to ground, its grid is about 25 volts negative with respect to ground, and the anode is about 115 volts positive with respect to ground. The other digit tubes of Fig. 2 normally have the same anode-cathode potential but have a normal grid potential of about 50 volts negative with respect to ground. The "Transfer Initiator" tube 104 has the same grid and anode potentials as the tubes "1" to "9," but its cathode is connected only to ground, as it is unnecessary to provide a potential-dividing network for grid-priming another tube, it being the last tube of the series to fire.

A positive potential impulse of sufficient potential to fire the "1" tube 101 is supplied to input terminal 100 (see Fig. 3 for its origin) whenever the impulse generator of Fig. 2 is to be given a cycle of operation. Such impulse comes from

the Multiplier unit shown in Fig. 3 and to be described hereafter. As the "1" tube 101 fires and becomes conducting, the anode supply conductor 143, due to resistors 114, 116, and 119, drops in potential to within about 15 volts of the normal

cathode potential of 5 volts negative as cathode-ground capacitor 142 charges. As capacitor 142 becomes charged, the potential of the cathode of the "1" tube rises to a point determined by the resistors 114, 116, and 119 in the anode supply

circuit, the potential drop of 15 volts within the tube and the cathode resistors 144, 145, and 146. Thus the cathode of "1" tube 101 rises from 5 volts negative to about 77 volts positive with respect to ground, impressing an impulse on point 108. Point 147 changes from 50 volts negative to about 1 volt positive, and the grid potential of the "2" tube 102 during this time rises to a point where the "2" tube fires and becomes conducting. The anode supply conductor dips in potential to

about 10 volts as the associated cathode-ground capacitor charges, causing the extinguishment of the "1" tube 101, as its anode potential drops below the cathode potential, which is momentarily maintained at about 77 volts by the charge in capacitor 142. In the same manner, the 3, 4, 5, 6, 7, 8, and 9 tubes fire successively, each tube as it fires extinguishing the preceding tube of the series. The "Transfer Initiator" tube 104 then fires, as its grid is connected to point 126 in the cathode supply circuit of "9" tube 131. This extinguishes the "9" tube as the potential of point 117 drops to 10 volts momentarily as capacitor 121 in the cathode supply circuit of the "Transfer Initiator" tube 104 is charging.

It will be observed that, while the digit tubes "1" to "9" have 4,250 ohms resistance in the anode supply circuit, due to resistors 114, 116, and 119, the "Transfer Initiator" tube 104 has only the resistors 114 and 116 in its supply circuit, amounting to 750 ohms, and only the 500-ohm resistor 116 between it and the .5-microfarad capacitor 121. As a result, while capacitor 121 is charging, there is a very high current flow through the "Transfer Initiator" tube 104, which

is abruptly reduced as capacitor 121 becomes

charged. The distributed inductance in the supply circuits for this tube, as the current suddenly reduces, causes an oscillatory rise in potential of the cathode, and momentarily there is a cessation of current flow in the tube, causing it to self-extinguish. However, during its brief period of conductivity, it produces a positive potential impulse on output conductor 106 and terminal 148 (see also Fig. 6), which initiates a discharge in "Transfer Control" tube 439 (Fig. 6), the purpose of which will be explained.

As the Impulse Generator digit tubes "1" to "9" (Fig. 2) fire successively, the cathode rise in potential of each is impressed on associated points such as points 108 and 109, all being propagated in one direction toward point 112. It follows that point 108 receives one impulse, point 109 receives two impulses, point 150 receives three impulses, and so on, point 112 receiving nine impulses.

For each impulse-receiving point such as point 150, there is provided a conductor, such as conductor 152, provided with a plurality of key switches, in this embodiment three in number, 153, 154, and 155. Switch 155 represents three in the units or decimal denomination 10^0 and, when operated, connects conductor 152 to output conductor 156, representing the 10^0 denomination. Similarly, switch 154 represents three in the tens or decimal denomination 10^1 and, when operated, connects conductor 152 to the output conductor 157, representing the 10^1 denomination. Switch 153 connects conductor 152 to output conductor 158, representing the hundreds or the decimal denomination 10^2 . Therefore it is possible to operate a key in each selected denomination, and, when the digit tubes "1" to "9" operate a cycle by firing in succession, the various output conductors receive a number of impulses corresponding to the value of the associated operated key. Resistors of 100,000 ohms such as resistor 159 connect each output conductor to ground to permit recovery of the conductor after receiving an impulse.

Repeated cycling of the impulse generator, assuming that the selected keys are kept operated during such cycling, results in the same pattern of impulses being repeatedly impressed on output terminals 160, 161, and 162 (see also Fig. 4). One cycle of the impulse generator corresponds to a single entry of the multiplicand factor, which is directed by the Denominational Distributor of Fig. 4 to the Accumulator of Figs. 6, 7, and 8 by means of terminals 170, 171, 172, 173, and 174 (Figs. 4, 6, 7, and 8) according to the stage of the multiplying operation, which is determined by the Stage Control unit of Fig. 5 in its effect on terminals I, II, and III (see Fig. 4 also). The Stage Control unit of Fig. 5 at the same time determines which digit of the multiplier factor set up on the keys of the Multiplier unit of Fig. 3 controls the recycling of the Impulse Generator of Fig. 2.

It is obvious that the impulse impressed on terminals 160, 161, and 162 by the firing of the "1" tube 101 will occur at the same time (assuming a key to have been operated in each bank), and the same is true for the output of each digit tube. It is obvious, therefore, that impulses occurring on the several conductors 156, 157, and 158 simultaneously are sent to the accumulator, and entry of data in the several orders of the accumulator may be going on simultaneously, necessitating a pause between each cycling of the

impulse generator to give time for transfer of carry-over data.

Carry-over data in the accumulator is transferred successively by denominations, commencing with the lowest denomination, and the transfer operation occurring between cycles of the impulse generator is initiated by the "Transfer Initiator" tube 104 (Fig. 2), which sends a transfer starting impulse over conductor 105 and terminal 148 (see Fig. 6) to the 10^0 denomination of the accumulator. On completion of the transfer operation, an impulse is impressed on terminal 175 (see Figs. 3 and 8), which, through the Multiplier unit of Fig. 3, causes a recycling of the Impulse Generator (Fig. 2) through a positive impulse impressed on terminal 100 (Fig. 2) through capacitor 176 of .000002 microfarad to the grid of the "1" tube 101.

Therefore, the Multiplicand unit of Fig. 2 always stands ready to issue a selected number of impulses, as determined by the operated Multiplicand keys, on each of output terminals 160, 161, and 162, when a positive impulse is impressed on terminal 100.

Capacitors, like capacitor 177, before described, of .001 microfarad slow down the operation of this impulse producer to about 10,000 impulses a second, and therefore one cycle of its operation of the ten tubes consumes about .001 of a second. The Accumulator functions much faster, the difference in speed being deliberately provided so that the generated impulses will not exceed in speed the acceptance rate of the Accumulator.

It will be readily perceived that there can be as many key banks in the Multiplicand unit as desired without increasing the number of tubes.

The general principle of the impulse generator unit of Fig. 2 is more fully set out in applicant Compton's co-pending application for United States Letters Patent, Serial No. 488,126, which was filed on the twenty-fourth day of May, 1943, and which issued on April 23, 1946, as Patent No. 2,398,771.

The denominational distributor

As stated before, the particular embodiment of this invention discloses three multiplicand denominations and three multiplier denominations.

In the Denominational Distributor unit shown in Fig. 4, the three horizontal rows of tubes represent the multiplicand denominations, and the three vertical columns represent the three multiplier denominations.

Thus, tubes 180, 183, and 186 represent the units multiplier denomination, tubes 181, 184, and 187 represent the tens multiplier denomination, and tubes 182, 185, and 188 represent the hundreds multiplier denomination. For purposes of convenience, these units, tens, and hundreds denominations are termed stages I, II, and III, respectively.

Tubes 180, 181, and 182 represent the hundreds multiplicand denomination, tubes 183, 184, and 185 represent the tens multiplicand denomination, and tubes 186, 187, and 188 represent the units multiplicand denomination. These have been denominated as 10^2 , 10^1 , and 10^0 denominations, respectively.

Output terminals are provided, as has been described, representing 10^0 , 10^1 , 10^2 , 10^3 , and 10^4 denominations and are numbered 170, 171, 172, 173, and 174, respectively.

An impulse issuing from the impulse generator

and impressed on terminal 160 is arranged to fire either tube 186, 187, or 188, depending on which one of stage control terminals I, II, or III is energized. I terminal 190 energizes or primes tubes 180, 183, and 186; II terminal 191 primes tubes 181, 184, and 187; and III terminal 192 primes tubes 182, 185, and 188. If I terminal 190 was primed as the impulse was received on terminal 160, representing 10^0 power of the multiplicand, then tube 186 would fire and become conducting and in so doing would issue an impulse on diagonal output conductor 193, ending in 10^0 terminal 170, which is the input to the 10^0 denomination of the accumulator (see Fig. 6). If, instead, the II terminal were primed, the tube 187 would fire and the output would be on conductor 194, connected to the terminal 171, which is the input to the 10^1 denomination of the accumulator. If the III terminal 192 were primed, the tube 188 would fire and the output would be on conductor 195, which is connected to the terminal 172, which is the input to the 10^2 denomination.

It will be seen that conductor 193 has only the cathode of tube 186 connected thereto, conductor 194 has the cathodes of tubes 183 and 187 connected thereto, conductor 195 has the cathodes of tubes 180, 184, and 188 connected thereto, conductor 196 has the cathodes of tubes 181 and 185 connected thereto, and conductor 197 has the cathode of tube 182 connected thereto. The following table discloses the routing of the impulses in different stages of a multiplying operation.

Generated Impulses Impressed on Terminal	Distributed to Accumulator Terminal
STAGE I	
160- 10^0	170- 10^0
161- 10^1	171- 10^1
162- 10^2	172- 10^2
STAGE II	
160- 10^0	171- 10^1
161- 10^1	172- 10^2
162- 10^2	173- 10^3
STAGE III	
160- 10^0	172- 10^2
161- 10^1	173- 10^3
162- 10^2	174- 10^4

Each of the Denominational Distributor tubes is arranged in a circuit that makes it self-extinguish if it fires, just as was explained in connection with the "Transfer Initiator" tube 104 (Fig. 2). All the tubes connected to the same diagonal output conductor have the same cathode supply circuits. The cathode of tube 186 is connected to ground by 50,000-ohm resistor 198 in parallel with .0005-microfarad capacitor 199. The cathode is also coupled to the output terminal 170 by the .01-microfarad capacitor 200.

In a similar manner, the cathodes of tubes 183 and 187 are connected to ground through resistor 201 in parallel with capacitor 202, and coupled to terminal 171 by capacitor 2030. The other cathode connections are similar and can be traced as follows: the cathodes of tubes 180, 184, and 188 are connected to ground by resistor 203 and capacitor 204, and coupled to terminal 172

by capacitor 205; the cathodes of tubes 181 and 185 are connected to ground by resistor 206 and capacitor 207, and coupled to terminal 173 by capacitor 208; and tube 182 is connected to ground by resistor 209 and capacitor 210 and is coupled to terminal 174 by capacitor 211.

The anodes of all the tubes in a horizontal row are supplied from the same terminal. For instance, the anodes of tubes 180, 181, and 182 are supplied with 75 volts positive potential from source 212 through resistor 213 of 250 ohms, point 214, and resistor 215 of 500 ohms. Point 214 is coupled to ground through capacitor 216 of .1 microfarad. In a similar manner, terminal 217 supplies anode potential to tubes 183, 184, and 185, and terminal 218 supplies anode potential to tubes 186, 187, and 188. With these circuit elements, when a tube fires, it automatically extinguishes because of the high initial current followed by an oscillatory rise in cathode potential as the associated cathode-ground capacitor becomes charged. As a tube fires, the positive rise in cathode potential is impressed on the associated output conductor.

The grids of all the tubes are normally heavily biased by reason of potential applied from the stage control unit of Fig. 5. Thus the tubes 180, 183, and 186 (Fig. 4) obtain their grid bias from I terminal 190 (see also Fig. 5); tubes 181, 184, and 187 obtain their grid bias from terminal 191; and tubes 182, 185, and 188 obtain their grid bias from terminal 192. This normal grid bias is 80 volts negative, but is relieved to 35 volts negative when in the primed state. For example, under normal circumstances, when stage I of the multiplying operation occurs, terminal 190 changes from 80 volts negative to 35 volts negative, which change is impressed on the grids of tubes 180, 183, and 186 each through a 500,000-ohm resistor, like resistor 219, a point like point 220, and a 50,000-ohm resistor, like resistor 221. Points like point 220 are coupled to the associated input conductor. Thus, point 220 is coupled to conductor 222 through a .00002-microfarad capacitor 223. If an impulse signal is received over any of terminals 160, 161, and 162 while I terminal 190 is primed, the corresponding ones of tubes 180, 183, and 186 will fire and self-extinguish, each firing of a tube passing on an impulse to the associated output conductor. Terminals I, II, and III are rendered primed in sequence by the Stage Control unit, and each stays primed until the Impulse Generator operates a number of times equal to the value of the corresponding operated multiplier key switch.

Stage control

The Stage Control is shown in Fig. 5 and comprises a Start tube 250 and three stage control tubes I, II, and III, numbered 251, 252, and 253, respectively.

The cathode of Start tube 250 is connected to ground through 50,000-ohm resistor 254. Its grid is connected through 50,000-ohm resistor 255 to points 256 and 257. Point 257 is connected on one side through 500,000-ohm resistor 258 to negative 150-volt supply conductor 259, and on the other side through 350,000-ohm resistor 260, point 261, 5000-ohm resistor 262, point 263, 250-ohm resistor 264, to Start Key switch 265, which, when closed, makes contact with 115-volt positive potential terminal 266. Key switch 265 must remain closed during an entire multiplying operation. Point 263 is coupled to ground by .5-microfarad capacitor 267 for stabilizing purposes, and point

256 is coupled to ground by .01-microfarad capacitor 268. When capacitor 268 charges, as key 265 closes, the grid of Start tube 250 loses control, and the tube fires, causing a potential rise at its cathode which is impressed on point 270 through .00005-microfarad capacitor 271. The anodes of tubes 251, 252, and 253 receive their potential from point 263 through 3,000-ohm resistor 272. During the slight delay of perhaps .001 second, while Start tube 250 is firing, the potential supply network of the I, II, and III tubes 251, 252, and 253 become stabilized, as do the bias voltages delivered to the grids of the tubes of the Denominational Distributor of Fig. 4, through terminals 190, 191, and 192. The cathode of each of tubes I, II, and III is connected on one side to ground through a 15,000-ohm resistor, like resistor 273 in parallel with a .002-microfarad capacitor, like capacitor 274 in series with a 1,000-ohm resistor, like resistor 275, and is connected on the other side to negative 150-volt conductor 259 through a 100,000-ohm resistor, like resistor 276, a point like point 277, and 100,000-ohm resistor like resistor 278. The grid of the I tube 251 is connected through 50,000-ohm resistor 289, point 270, 500,000-ohm resistor 281 to point 282 connected to ground through 50,000-ohm resistor 283, and to 150-volt negative conductor 259 through 250,000-ohm resistor 284. The grid of the II tube 252 is connected to and receives its bias from point 277, which is relieved when I tube 251 is conducting, so that a positive potential impulse impressed on conductor 285, which is coupled to the grids of tubes II and III, each through a capacitor like .00002-microfarad capacitor 286 connecting to point 287 of the II tube grid circuit, will fire the II tube and not the III tube. The normal grid bias of tubes II and III with respect to the associated cathode is about 80 volts negative and, when primed by reason of conduction in the preceding tube, is about .35 volts negative. The firing impulses on input conductor 285 are adjusted to fire a primed tube only. Thus, the sequence of operation of the Stage Control unit of Fig. 5 commences with the firing of the Start tube 250, and after a short interval, during which the supply networks adjust themselves, the I tube 251 fires and becomes conducting. This act causes a rise in potential of the cathode of the I tube, as has been explained, which primes the grid of the II tube. This priming potential is also impressed through point 288 and conductor 289 to terminal 190 (see also Fig. 4), which primes the grids of the I column of Denominational Distributor tubes 180, 183, and 186 (Fig. 4). The rise in potential of the cathode of the stage I tube 251 (Fig. 5) is also conveyed by conductor 290 to terminal 291 (see also Fig. 3) to initiate the 10^0 cycle of the Multiplier unit. At the conclusion of a cycle of the Multiplier unit under control of the 10^0 denominational keys, a positive potential signal is impressed on terminal 292 (see Figs. 3 and 5), which fires the II stage tube 252 (Fig. 5), resulting in the extinguishment of the I tube 251, its anode dropping in potential as capacitor 293 of the II tube cathode is charging, while at the same time the capacitor 274 is discharging. The firing of the II tube 252 also causes a rise in potential on terminals 191 and 294, priming tubes 181, 184, and 187 (Fig. 4) of the Denominational Distributor and causing the commencement of a cycle of operation of the Multiplier unit under control of the 10^1 denominational keys. At the conclusion of this 10^1 multiplier cycle, terminal 292 (Figs. 3 and 5) receives another potential im-

pulse, which causes the firing of the III Stage Control tube 253 (Fig. 5), the extinguishment of the II Stage Control tube 252, the priming of the III terminal 192 affecting tubes 182, 185, and 188 (Fig. 4) of the Denominational Distributor, and causing a positive potential rise on terminal 295 (Figs. 5 and 3) to commence a cycle of operation of the Multiplier unit under control of the 10^2 denominational keys. At the conclusion of the 10^2 cycle of the Multiplier unit of Fig. 3, an impulse is impressed on terminal 292 without result, as there are no more stage tubes to fire. At this point, the multiplication operation is complete, and the Start key may be opened and the key switches of the Multiplier unit and the Multiplicand unit restored to unoperated condition. It is to be noted that the last impulse on terminal 292 may be used to control any type of automatic key restoring means, by providing a tube to fire after the III Stage Control tube, which can operate, for instance, an electromagnet. Such key restoring means is not shown, as it is no part of the invention and is old in the calculating machine art.

The multiplier unit

The Multiplier unit is shown in Fig. 3 and comprises nine digit tubes 1, 2, 3, 4, 5, 6, 7, 8, and 9 and numbered 300, 301, 302, 303, 304, 305, 306, 307, and 308, a relay tube 309 for creating an impulse to cause a step of operation of the Stage Control unit by route of terminal 292, two delay tubes 310 and 311, which time the delivery of the Multiplicand unit recycling impulses to terminal 100, and three denominational banks of nine digit key switches representing the units, tens, and hundreds decimal denominations, for convenience referred to as 10^0 , 10^1 , and 10^2 denominations.

In a multiplying operation, the multiplier factor is set up by closing one key switch in each denominational bank. The Multiplier unit operation is by cycles, each key bank controlling the operation of the digit tubes during one of the cycles by determining where in the series of nine digit tubes the operation of a cycle commences, and consequently how many tubes will operate in that cycle. The digit tubes are connected to be operated serially one at a time toward the "9" tube, in response to impulses commonly received by the grids of all the tubes over conductor 320, which originate from the last transfer control tube 321 (Fig. 8) and are impressed on terminal 175. Thus, after an entry of the multiplicand factor into the Accumulator, the transfer cycle takes place, and, at the conclusion of the transfer cycle, an impulse on terminal 175 causes a step of operation of the Multiplier unit's tubes. Consequently, the number of tubes to operate in a particular denominational cycle of the Multiplier unit determines the number of times the multiplicand factor is entered into the Accumulator, and into what denominations of the Accumulator it is entered is determined by the Denominational Distributor, which, with the Multiplier unit, is jointly controlled by the Stage Control unit to correlate the multiplying operation by the denomination of the Multiplier unit in control.

If, for example, it is desired to multiply by five, the "5" key 322 in the 10^0 denomination is operated, the "0" keys 340 and 341 in the 10^1 and 10^2 banks are operated, the multiplicand factor is set up (Fig. 2), and the Start key (Fig. 5) is closed. The Denominational Distributor

tubes 180, 183, and 186 (Fig. 4) become primed, and a positive potential impulse is given to terminal 291 (Figs. 5 and 3), which is conveyed through rectifier 323 (Fig. 3) shunted by 500,000-ohm resistor 324, and through .01-microfarad capacitor 325, stage initiating conductor 299, and key switch 322 to point 326 in the grid circuit of "5" tube 304, temporarily relieving the normal controlling bias, causing it to fire and become conducting. The cathode potential supply circuit of tube 304 has therein a 15,000-ohm resistance which causes it to rise suddenly in potential, and this is conveyed by conductor 327 and .001-microfarad capacitor 328 to a common multiplier output conductor 329, to point 330, and from there through .0002-microfarad capacitor 331 to fire delay tube 310, which in turn fires delay tube 311, which passes a cathode positive potential impulse on to terminal 100 to cycle the Multiplicand Unit and enter the multiplicand in the Accumulator under control of stage I tubes of the Denominational Distributor. At the conclusion of the multiplicand entry, the transfer cycle takes place in the Accumulator, and at the conclusion of the transfer cycle an impulse is impressed on terminal 175 (Figs. 8 and 3), which impulse is impressed through individual capacitors, like .00005-microfarad capacitor 332, onto the grid circuits of all the nine digit tubes of the Multiplier unit. Each of such tubes' grids has a normal controlling bias which is primed to near the firing point if the digit tube of next lower value is conducting, and hence such priming causes the positive potential impulse on conductor 320 to fire the "6" tube 305 to the exclusion of any other of the Multiplier unit digit tubes. This causes a positive potential impulse on conductor 329, which causes a cycle of the Multiplicand unit and in addition causes a rise on all the digit tube cathodes, because all are coupled to conductor 329. The cathode of the conducting "5" tube is within fifteen volts of the anode potential, and the additional rise caused by the firing of the "6" tube causes a cessation of current flow in the "5" tube, and it is extinguished. This operation continues, the "7," "8," and "9" tubes firing in succession, giving a total of five cycles of Multiplicand operation, which corresponds to the value of the operated "5" key 322. The condition of conduction in the "9" tube 308 primes the relay tube 309 by a portion of the cathode rise being conveyed by point 333, resistor 334, point 335, resistor 336, and conductor 337 to the grid circuit of tube 309. The grid of tube 309 is also connected by a .00005-microfarad capacitor 338 to conductor 320, and, upon receipt of an impulse on terminal 175 while "9" tube 308 is conducting, the relay tube 309 will fire, extinguishing the "9" tube and passing a positive potential impulse originating at its cathode, over conductor 339 to terminal 292 (see Fig. 5) to cause the firing of the II Stage Control tube 252 (Fig. 5) and the extinguishment of the I Stage Control tube. An impulse is consequently impressed on terminal 294 (Figs. 3 and 5), which is conveyed through the operated "0" key switch 340 and conveyed through point 335, resistor 336, and conductor 337 to fire the relay tube 309. As a consequence, no action occurs in the Multiplicand unit, and the Stage Control unit is actuated to cause the III Stage tube 253 (Fig. 5) to fire. This impresses an impulse on terminal 295 (Figs. 3 and 5), which, as "0" key switch 341 is closed, again immediately fires the relay tube 309, and the operation is over, and the multiplicand has

been entered five times into the Accumulator. If, in the example just given, instead of the "0" key switch 341 in the 10² denomination of the Multiplier unit having been operated, it was the "8" key 342 that was operated, then the last impulse received on terminal 295 would have fired the "2" tube 301, and, as a consequence, the Multiplicand unit would be actuated and the Multiplicand factor would be entered into the Accumulator under control of the stage III tubes of the Denominational Distributor. Such multiplicand entry would be made as each of the tubes 2, 3, 4, 5, 6, 7, 8, and 9 of the Multiplier unit fired in succession, and then the relay tube 309 would fire, ending the operation. Relay tube 309 is arranged in a circuit so that it self-extinguishes after it is rendered conducting. Tube 310, when conducting, is thereafter extinguished by the firing of tube 311, and the tube 311 is self-extinguishing, as will be apparent as the circuits and circuit elements of Fig. 3 are specified.

All of the anodes of tubes 1 to 9 inclusive are supplied with 115 volts positive potential by being connected to conductor 350, which is connected through 3,500-ohm resistor 351, point 352, 500-ohm resistor 353, point 354, and 250-ohm resistor 355 to 115-volt positive source of potential 356. The anode of tube 309 receives potential from point 352, and point 354 is coupled to ground through .5-microfarad stabilizing capacitor 357. The cathode of each digit tube is connected to ground on one side through a 15,000-ohm resistor, like resistor 358 associated with the "4" tube, and is connected to negative 150-volt supply conductor 359, through a 100,000-ohm resistor, like resistor 360, a point like point 361, and a 100,000-ohm resistor, like resistor 362. This gives each cathode a normal potential of 10 volts negative, which rises to 80 volts positive when the tube is conducting. Points like point 361 supply the grid bias for the succeeding tube, and normally it is 80 volts negative and rises to 35 volts negative when the associated tube is conducting. Points like point 361 are connected to the succeeding tube's grid through a 250,000-ohm resistor, like resistor 363, a point like point 326, a 250,000-ohm resistor like resistor 364, a point like point 365, and a 50,000-ohm resistor like resistor 366. Tube 309, which originates the impulses which operate the Stage Control unit, receives its anode potential from point 352. Its cathode is connected to ground through 50,000-ohm resistor 367 in parallel with .0005-microfarad capacitor 368, and to the negative potential supply conductor 359 through 650,000-ohm resistor 369. The grid of tube 309 receives its potential through 50,000-ohm resistor 336 and 250,000-ohm resistor 334 from the point 333 in the negative leg of the cathode supply circuit of the "9" tube. With the circuit values just given, the tube 309 will self-extinguish when rendered conducting, and in firing sends an impulse over conductor 339.

The before-mentioned delay tubes 310 and 311 are arranged to fire in succession on the firing of any one of the digit tubes 1 to 9, the firing of tube 311 giving rise to a positive potential impulse at terminal 100 to operate the impulse generator. The purpose of the consequent delay is to permit the stabilization of the potentials in the Stage Control and Denominational Distributor units after a denominational shift. The anode of tube 310 receives its potential through 3,500-ohm resistor 371, 500-ohm resis-

istor 372, point 373, and 250-ohm resistor 374, which is connected to a 115-volt positive supply terminal. Point 373 is coupled to ground by means of .5-microfarad capacitor 3750. The cathode of tube 310 is connected on one side to ground through 15,000-ohm resistor 375 in parallel with .001-microfarad capacitor 376, and on the other side through 150,000-ohm resistor 377, point 378, 300,000-ohm resistor 379, and point 380 to a negative 150-volt source of potential 387. The grid of tube 310 receives its normal controlling bias through 50,000-ohm resistor 381, point 382, 500,000-ohm resistor 383, and point 384, which is connected on one side through 50,000-ohm resistor 385 to ground, and through 250,000-ohm resistor 386 on the other side to point 380, which leads to the 150-volt negative terminal 387. When tube 310 is fired by receipt of an impulse through capacitor 331, its cathode rise in potential is impressed through resistor 377, point 378, and 500,000-ohm resistor 388 to the grid of tube 311, after the charging of .001-microfarad delay capacitor 389, which couples point 390 to ground. The anode supply for tube 311 is taken from point 391, and the cathode is coupled to ground through 50,000-ohm resistor 392 in parallel with .002-microfarad capacitor 393. As tube 311 fires, tube 310 is extinguished due to the drop in potential of its anode, and tube 311 passes on an impulse to the impulse generator 100 and then self-extinguishes.

The accumulator

Six denominational banks are provided in the Accumulator. The units or 10^0 bank and the tens or 10^1 bank are shown in Fig. 6, the hundreds or 10^2 bank and the thousands or 10^3 bank are shown in Fig. 7, and the tens of thousands or 10^4 bank and the hundreds of thousands or 10^5 bank are shown in Fig. 8.

There are ten digit tubes in each bank, but those tubes representing the digits 8, 7, 6, 5, 4, and 3 in each bank are omitted in the drawings, as shown by dotted lines 400 in Fig. 6, for instance, such omission being only of a repeating network pattern of tubes and circuits which are fully shown in connection with the remaining tubes of each bank. It will be understood that the number of tubes in a bank can be increased or decreased to make it of any size, so as to serve other than decimal numerical notation. Associated with each denominational bank are a transfer tube "T" and a Transfer Control tube "TC" for accomplishing denominational transfers of carry-over data.

The units bank 10^0 , being typical, will be described as representative of all the banks as regards the ring of digit tubes. Anode voltage of 115 volts positive is supplied from terminal source 401 through 250-ohm resistor 402, point 403, and 7,500-ohm resistor 404 and conductor 405, to which all the anodes are directly connected. The cathode of each tube is connected to ground through a 15,000-ohm resistor like resistor 406 in parallel with a .002-microfarad capacitor like capacitor 407, and is also connected to negative supply conductor 408, supplied with 150 volts negative, through a 100,000-ohm resistor like resistor 409, a point like point 410, and a 100,000-ohm resistor like resistor 411. Points like point 410 are connected to the grid of the succeeding tube in the ring through a 500,000-ohm resistor like resistor 412, a point like point 413, and a 50,000-ohm resistor like

resistor 414. Points like point 413 are each coupled to a common input conductor 417 for the denomination through a .00002-microfarad capacitor like capacitor 415. A switch like switch 416 is provided between ground and the grid of each "0" tube, so that, upon temporary closing of the switch, the "0" tube will fire and become conducting. As a tube becomes conducting, it primes the grid of the next succeeding tube of the ring, as a conducting tube's cathode rises in potential. This relieved bias on the succeeding tube makes it more susceptible to a positive input impulse on conductor 417 than any other tube of the ring. Circuit values given for the 15 Denominational Distributor relay tubes will cause the output from them in the form of impulses to fire a primed tube of the Accumulator but not an unprimed one. Conductor 420 closes the denominational ring by connecting the "0" 20 tube cathode priming point 421 to the "1" tube's priming point 422. The anode supply conductor will temporarily drop in potential as the cathode-ground capacitor of a firing tube charges, while the cathode of the preceding priming tube's 25 cathode-ground capacitor is discharging. This causes a temporary cessation of anode-cathode potential in the preceding tube, extinguishing it. Thus a number of impulses impressed on output conductor 417 will cause the same number 30 of tubes to fire successively in the ring, and the conducting tube represents the accumulated data. The data is read by observing the glow in the tubes or by sensing their condition electro-mechanically, as shown in the United States 35 patent application of Joseph R. Desch and Robert E. Mumma, Serial No. 325,040, filed March 20, 1940.

It is arranged to have a transfer tube 423 fire each time the "0" tube fires, indicating one full 40 cycle of operation of the ring, such transfer tube later being extinguished to create an impulse to cause a step of operation in the ring of next higher denomination. Switches like switch 418 in the anode supply of each "T" tube are opened 45 before the zeroizing switches are closed to prevent the "T" tubes from firing. After zeroizing all of the Accumulator, the switches, like switch 418, are closed.

Input conductor 417 receives impulses from 50 terminal 470, which is the 10^0 output from the Denominational Distributor (Fig. 4).

Transfer tube 423 receives its anode potential from 135-volt positive terminal 425, through switch 418, 250-ohm resistor 426, point 427, and 55 7,500-ohm resistor 428. Point 427 is coupled to ground by .1-microfarad capacitor 429. Tube 423 receives its cathode potential by being connected through 10,000-ohm resistor 430 to ground. The grid of tube 423 receives its potential by 60 being connected through 50,000-ohm resistor 431, point 432, and 500,000-ohm resistor 433 to point 434, which is connected through 50,000-ohm resistor 435 to ground on one side, and through 250,000-ohm resistor 436 to the negative 150-volt 65 conductor 408 on the other side. The transfer tube is thus ordinarily non-conducting but is rendered conducting by a positive impulse originating at the cathode of the "0" tube 437 when the "0" tube fires, said impulse being impressed through .00005-microfarad capacitor 438 70 onto grid bias point 432.

At the initiation of the transfer cycle caused by a positive potential impulse received on terminal 448 leading to the grid of the Transfer Control 75 tube 439, tube 439 is fired, and, upon becoming

conducting, its cathode rises in potential, which rise is transmitted through .01-microfarad capacitor 440 and impressed on the cathode of transfer tube 423. If tube 423 is conducting, it is by that impulse from tube 439 extinguished, and its anode rises suddenly in potential, passing on said positive impulse through .0005-microfarad capacitor 441 and through rectifier 442 oriented to pass positive impulses to the input conductor for the next higher denominational bank. Rectifier 442 is shunted by 50,000-ohm resistor 443. Thus, if the denominational ring of 10^0 bank has, during one cycle of the impulse generator, passed through zero, transfer tube 423 will have fired, and later, at the conclusion of the cycle of the impulse generator, transfer control tube 439 will fire and extinguish tube 423, passing on the transfer impulse to the next higher order, causing the addition therein of one unit. Transfer Control tube 439 obtains its anode potential from 115-volt positive source 445, through 250-ohm resistor 446, point 447, and 4,000-ohm resistor 448. Point 447 is coupled to ground through .1-microfarad capacitor 449. The cathode of tube 439 obtains its potential by being connected to ground through 15,000-ohm resistor 4490 in parallel with .01-microfarad capacitor 450, and to negative 150-volt source 451 through 150,000-ohm resistor 452, point 453, and 300,000-ohm resistor 454. Point 453 is coupled to ground by .002-microfarad delay capacitor 455. The grid of tube 439 obtains its normal bias through 50,000-ohm resistor 456, point 457, and 500,000-ohm resistor 458, which is connected to point 459, grounded on one side through 50,000-ohm resistor 460 and on the other side connected through 250,000-ohm resistor 461 to negative supply terminal 451. Point 457 is connected to terminal 148 through .00005-microfarad capacitor 462. With the circuit elements as given, transfer control tube 439 fires on receipt of a positive impulse on terminal 148 and issues a positive impulse through capacitor 440 to extinguish the transfer tube, if it was conducting, thereby causing the transfer unit to be added in the next higher denomination. Tubes 439 and 470 have their anodes connected to the source of potential 445 over a common resistor 448. In a manner similar to that by which the tubes of the impulse generator extinguish one another, conduction beginning in either tube 439 or 470 will extinguish the other tube of the pair if it is already conducting. The rise in potential of point 453, as tube 439 fires, is conveyed, after the charge of the delay capacitor 455, to the grid of the 10^1 bank's Transfer Control tube 470, to fire it. Point 453 is the grid bias point for tube 470. Tube 470 is supplied with the same potentials and circuits as is tube 439 and, on being fired, extinguishes the transfer tube for the 10^1 bank if conducting, passing on an impulse to the input conductor of the 10^2 bank by way of terminal 471 (see also Fig. 7). The firing of Transfer Control tube 470 for the 10^1 denominational bank also passes on an impulse over terminal 472 to fire the Transfer Control tube for the 10^2 denominational bank after a delay capacitor similar to 455 has charged. Input conductor 473 of the 10^1 denominational bank contains a rectifier 474 to pass positive potentials only in the direction of the arrow to prevent absorption of positive impulses by the circuits of the Denominational Distributor originating when the transfer tube of next lower denomination is extinguished. Such a rectifier is provided in each order except the lowest. Each rectifier such as

rectifier 474 is shunted by a 50,000-ohm resistor such as resistor 475. Transfer tube output from the 10^3 denomination (Fig. 7) is over terminal 476 (see Fig. 8), and output from the Transfer Control tube of the 10^3 denomination is over terminal 477.

The 10^5 denominational bank (Fig. 8), being for overflow purposes only, receiving impulses only from the 10^4 denominational bank through point 493 and rectifier 501, has appended to its input circuit capacitor 502 of .0005 microfarad, resistor 503 of 50,000 ohms, rectifier 504, and resistor 505 of 50,000 ohms to simulate the circuit elements appended to the lower denominational banks by reason of their connection to the Denominational Distributor unit.

Transfer tube 510 is provided to show how additional overflow denominational banks may be added to the Accumulator or how a signal may be made indicating a full Accumulator.

The output from the transfer tube of the 10^5 denominational order is shown by dotted line 490 (Fig. 8) to indicate how transfers may be made to higher orders.

Transfer tube 510 is arranged in a self-extinguishing circuit, receiving 75 volts positive anode potential from source 511, through resistor 512 of 250 ohms, point 513, and resistor 514 of 500 ohms. Point 513 is coupled to ground through capacitor 515 of .1 microfarad. The cathode is connected to ground through 50,000-ohm resistor 516 in parallel with .0005-microfarad capacitor 517.

Since there are no entries from the differential impulse generator in the overflow banks, there is no need to delay the transfer entries therein. Tube 510 is accordingly primed from the "9" tube along with the "0" tube and is fired by the same impulse on impulse conductor 492 which fires the "0" tube. The firing of tube 510 along with the "0" tube causes a transfer to a higher overflow or causes an overflow signal, if no higher order, to be made without delay when the "0" tube fires.

The positive impulse output of the Transfer Control tube 321 of the last order is conveyed over terminal 175 to step the Multiplier unit (Fig. 3) a step, as has been explained.

Delay capacitors similar to capacitor 455 in the circuits of the Transfer Control tubes delay the firing of the Transfer Control tubes in the sequence to allow for transfer entries, if they occur, in the various orders.

When the 10^5 denomination passes through zero, a signal appears on conductor 490, which may be used for signaling an overflow of data.

The circuit elements of the Accumulator have been chosen to give it an impulse acceptance rate at approximately twice the rate of production thereof by the Impulse Generator.

60

Operation

Referring to Fig. 1, the operation of the multiplying device will be summarized.

The Accumulator is zeroized by operation of the zeroizing keys in all orders of the Accumulator after removing anode potential temporarily from the Transfer tubes. As an example problem, the multiplicand factor chosen will be 658, and the multiplier factor chosen will be 123. These factors are set up on the associated keys and the Start key is closed (Fig. 5), which fires the Start tube. After a short delay, the "I" Stage Control tube is fired, priming column I of the Denominational Distributor tubes and sending an impulse to the 10^0 input of the Multiplier unit

75

(Fig. 3), which is routed through the "3" key switch to fire the "7" tube of the Multiplier unit. The firing of the "7" tube fires the two Delay tubes 310 and 311 in series, and the last to fire sends an impulse over terminal 100 (see also Fig. 2) to the Multiplicand unit to fire the nine digit tubes in succession. This act sends out eight impulses on terminal 160, five impulses on terminal 161, and six impulses on terminal 162 (see Fig. 4) to the Denominational Distributor, causing the relaying of eight impulses to the 10^0 bank of the Accumulator over terminal 170 (see Fig. 6), five impulses over terminal 171, and six impulses over terminal 172 (see Fig. 7), actuating the Accumulator accordingly. The Transfer Initiator tube (Fig. 2) is then fired, which sends an impulse over terminal 148 (see Fig. 6) to fire the Transfer Control tube of the 10^0 bank of the Accumulator. The Transfer Control tubes are fired serially, and the associated transfer tubes, if any are conducting, will be extinguished serially thereby. It will be apparent that, after this first entry, none will be conducting. The Transfer Control tube of the 10^5 denomination of the Accumulator (Fig. 8) passes on an impulse over terminal 175 (see also Fig. 3), which fires the primed "8" tube of the Multiplier unit, and, after the two delay tubes 310 and 311 have fired, an impulse is sent over terminal 100 (see also Fig. 2) to cause another cycle of operation of the Impulse Generator to enter the number 658 into the Accumulator, as before described. As yet, no transfer having taken place, the number 206 stands in the Accumulator. As the 10^0 and 10^2 denominational rings of the Accumulator have passed through zero, and the 10^1 ring stands on zero, the Transfer tubes of the 10^0 , 10^1 , and 10^2 denominational rings of the Accumulator are conducting. As the Transfer Control tubes are serially operated, first the 10^0 transfer tube is extinguished, entering one unit into the 10^1 denomination, making the Accumulator read 216. Secondly, after a suitable delay, Transfer Control tube 10¹ fires, the 10¹ Transfer tube is extinguished, sending a unit to the 10^2 denominational ring, making the Accumulator read 316. Lastly, after a suitable delay, the 10² Transfer Control tube is fired, extinguishing the 10² transfer tube, sending a unit to the 10³ denominational ring, making the Accumulator read 1316, which is the sum of 658 plus 658. The number 658 is entered once more in stage I by reason of the firing of the "9" tube of the Multiplier unit, and the Accumulator after the transfer then reads 1974. The last tube in the chain of Transfer Control tubes again sends an impulse over terminal 175 to the Multiplier unit, but this time the Stage Control Shift tube 309 (Fig. 3) fires and sends an impulse over terminal 292 (see also Fig. 5), which fires the stage II tube 252, extinguishing the stage I tube, priming the stage II column of the Denominational Distributor unit, and delivering an impulse to terminal 294 (Fig. 3), serving the 10^1 bank of keys of the Multiplier unit. As key "2" has been operated therein, the "8" tube will accordingly fire, firing the delay tubes 310 and 311 and thereafter actuating the Multiplicand unit to send out the same pattern of impulses, representing "658," to the Denominational Distributor. At this time, the stage II column of tubes of the Denominational Distributor are primed, and the impulses are accordingly routed to the 10^1 , 10^2 , and 10^3 denominations of the Accumulator. After the stage II entries have been made twice, the Stage Control unit shifts to stage III, wherein the 10^2 , 10^3 , and

10^4 denominations of the Accumulator are actuated, the entry of the multiplicand factor being made but once, as the 10^2 digit of the multiplier factor is 1. The multiplying operation is now complete. The final firing of the Stage Control shift tube 309 (Fig. 3) has no effect on the Stage Control tubes of Fig. 5, as III tube 253 primes no other tube.

The Start key may now be opened, and all of the tubes except those in the Accumulator representing the product data will be in extinguished condition. The device is now ready for another multiplying operation, which may be performed with or without returning the Accumulator to zero.

It is apparent that the key switches of the Multiplier and Multiplicand units may be controlled in any manner by record material according to well-known practices for the automatic setting up of factors.

The disclosed device is not to be deemed limited to the exact tubes, circuit elements, and time constants specified, as they are but illustrative of one embodiment of the invention.

What is claimed is:

1. A tens transfer device for an electric impulse counting device of the type which is operable by impulses from an impulse source and includes a plurality of denominational input conductors for receiving electric impulses from the input source and an electron tube counting ring coupled to each input conductor, said rings each including a tube for each denominational digit including zero, the combination of a transfer electron tube coupling a lower denominational ring to the next higher denominational ring; circuits supplying operating potential for each of said transfer tubes and connecting them to the lower associated ring so as to be rendered conducting when the said lower rings pass through zero and coupling them to the input conductor of the next higher denominational ring at a point so as to pass on an electric impulse to it when said transfer tube becomes extinguished; an extinguishing electron tube for each transfer tube; means connecting the extinguishing tubes in an operative chain from the lowest denominational order to the highest so that, if conduction is commenced in the tube associated with the lowest denomination, said extinguishing tubes are rendered conducting serially; means coupling each extinguishing tube to its related transfer tube to enable conduction occurring in the extinguishing tube to cause its related transfer tube to be extinguished; start means for the chain of extinguishing tubes, which start means, when given an electric impulse, starts conduction in the first extinguishing tube of the chain; and an extinguishing tube output conductor connected to the circuit of the last extinguishing tube to have an electric impulse impressed thereon when the last extinguishing tube is rendered conducting.

2. In combination, a plurality of denominational accumulator elements differentially operable cyclically through zero; differential means to operate the denominational accumulator elements in cycles; transfer means coupling each two adjacent denominational accumulator elements to form a totalizer, said transfer means being each conditioned when one of the associated denominational accumulator elements passes through zero so as to be later actuatable to carry a unit of data to the other denominational accumulator elements associated therewith; transfer operating control means operable to

affect each transfer means in succession from one end of the totalizer to the other to actuate the conditioned transfer means serially; means actuated by the differential means upon completion of a cycle of operation thereof to start an operation of the transfer operating control means; and means actuated by the transfer operating control means upon the completion of the operation thereof to initiate another cycle of operation of the differential means.

3. In combination, a plurality of denominational elements differentially operable cyclically through zero; differential means selectively operable in cycles to operate selected denominational elements to enter data therein; transfer means coupling the adjacent denominational elements to form a totalizer, said transfer means being each conditioned when one of the associated denominational elements passes through zero so as to be later actuatable to carry a unit of data to the other denominational element associated therewith; transfer operating control means operable to affect each transfer means in succession from one end of the totalizer to the other to actuate the conditioned transfer elements serially; means actuated by the differential means upon the completion of a cycle of operation thereof to start an operation of the transfer operating control means; and means coupled to the transfer operating control means and to the differential means and actuated by the transfer operating control means upon completion of an operation thereof to initiate another cycle of operation of the differential means.

4. In a multiplying device, the combination of a totalizer including denominational carry-over transfer means operable at the conclusion of an entry of data into the totalizer to make accrued transfers, said transfer means issuing a signal at the conclusion of its operation; data entering means coupled to the totalizer, said entering means being actuatable in cycles to enter in a cycle a selected factor into the totalizer and including a control signal generating means operable at the conclusion of an entering cycle; means for applying the control signals to the transfer means to cause an operation thereof; and means operable under control of the first-mentioned signal to initiate a cycle of operation of the data entering means, said means being selectively settable to respond to the end of transfer signal a number of times as selected, and including means operable to initiate a cycle of operation of the data entering means upon each response.

5. In a multiplying device, the combination of a totalizer equipped with transfer means conditioned during a data entering cycle and actuatable later to cause accrued transfers and to issue a signal; a data entering device coupled to the totalizer and actuatable in cycles to enter a selected factor into the totalizer and afterward to initiate an operation of the transfer means to actuate the conditioned transfer means; and a means coupled to the data entering device to actuate the data entering device a selected number of times in steps and also connected to the transfer means whereby the signal issued at the end of a transfer operation causes a step of operation of said data entering device actuating means.

6. In combination, a plurality of gaseous discharge electron tubes constituting a first group, each having at least an anode, a cathode, and a control element; means supplying anode-cathode potential and normally controlling control element bias potential to each of said tubes;

means to cause one or more of said tubes to become conducting by temporarily reducing the control bias; a gaseous discharge electron control tube for each tube of the first group, each control tube having at least an anode, a cathode, and a control element; circuit means supplying each control tube with anode-cathode potential and normally controlling bias potential; means connecting the control tubes into an operative

10 series whereby, if conduction is commenced in the first control tube of the series, they will fire automatically one at a time in sequence; means connecting each control tube with the associated tube of the first group so that, when a control tube fires, it extinguishes the associated tube if it be conducting; and means to fire the first control tube of the series.

7. A tens transfer device for a totalizer of the type which is made up of denominational electron tube counting units and having an input means for each unit, the combination of a transfer electron tube for each unit; connections between each transfer tube, a potential source, and a certain tube of the associated unit so that said transfer tube for a unit is rendered conducting each time said certain tube of the associated unit is rendered conducting; means connecting a point in each transfer tube's potential source connections to the input means of another unit to form said units into a series, each time a transfer tube is rendered non-conducting there being an impulse created and impressed on the input means of said other unit; and means operative to cause in a serial manner the extinguishment of those transfer tubes that are conducting at a given period of time.

8. A tens transfer device for a totalizer of the type which is made up of a plurality of denominational groups of electron tubes operable step by step to accumulate amounts, there being in each group an input means and a tube for each digit in the denomination and a zero tube, the combination of a transfer electron tube for each group; means to supply operating potential to the transfer tubes; means coupling the zero tube of a group to the associated transfer tube so that conduction commencing in the zero tube causes the associated transfer tube to become conducting; means connecting the groups of tubes together in a series by coupling the transfer tube of one group to the input means of the group next in the series; and means coupled to the transfer tubes and, when operated, applying an extinguishing action to each transfer tube in turn, beginning at the first of the series, any of said transfer tubes, when extinguished, impressing an impulse on the input means of the next group to operate the next group a step.

9. In combination, a plurality of denominational electron tube counter rings arranged in ascending orders, each ring being operable cyclically through zero by positive electric impulses; an input conductor for each counter ring; positive impulse generating relay devices connected to each input conductor, the connection to each input conductor above the lowest order being through a rectifier which passes only positive electric impulses to the input conductor; a transfer positive impulse generator unit associated with each counter ring, each of which transfer generators is coupled to its associated ring to be conditioned to create a positive electric impulse each time the associated ring passes through zero means connecting the transfer generator for a counter ring to the input conductor for the

next higher order through a rectifier oriented to pass positive electric impulses only in the direction of said input conductor of next higher order, said rectifiers preventing dissipation of relay-produced electric impulses in the transfer generator or vice versa; and means to actuate the relay devices and the conditioned transfer generators at different times.

10. A tens transfer device for a totalizer of the type which is made up of a plurality of cyclically operable denominational accumulating units operable in response to impulses to accumulate amounts and having an input conductor for each unit, the combination of a transfer electron tube for each unit, means connecting each transfer tube in an operating potential circuit which includes means which, when the tube passes from a conducting state to a non-conducting state, gives rise to a positive potential impulse at an impulse point in the circuit; means connecting each transfer tube to its associated unit so that the transfer tube is rendered conducting once each cycle of operation of the unit; means coupling the impulse point in the transfer tube operating circuit of each transfer tube to the input conductor of another unit to form an operative chain of the units so that the extinguishment of conduction in a transfer tube passes on an operation-inducing electric impulse to the next unit in the chain; and means to actuate the transfer tubes related to the various units to become non-conducting serially, starting with the beginning unit of the chain and proceeding to the last unit of the chain.

11. A tens transfer device for an accumulator of the type which is made up of a plurality of cyclically operable denominational accumulating units operable in response to impulses to accumulate amounts and having an input means for each unit, the combination of a gaseous discharge electron transfer tube for each unit, each transfer tube including at least an anode and a cathode; in an operating potential supplying circuit for each transfer tube including an anode supply portion which includes a resistance so that, when a transfer tube is rendered non-conducting, a positive potential impulse is created at the anode; means connecting each transfer tube to its associated denominational unit to be controlled thereby so that the transfer tube is rendered conducting once each cycle of operation of the unit; means coupling the anode of each transfer tube to the input means of another unit to form an operative chain of the units so that the extinguishment of conduction in a transfer tube passes on an operation-inducing impulse to the next unit in the chain of units; and means coupled to the transfer tubes to cause any conducting transfer tubes related to the units to become non-conducting serially, starting with the beginning unit of the chain.

12. A tens transfer device for an accumulator of the type which is made up of a plurality of cyclically operable denominational units operable in response to impulses to accumulate amounts and having an input conductor for each unit, the combination of a transfer electron tube for each unit; an operating potential supply circuit for each transfer tube, said circuit including means which, when the tube passes from a conducting state to a non-conducting state, gives rise to a positive potential impulse at an impulse point in the circuit; means connecting each transfer tube to its associated unit to be controlled thereby so that the transfer tube is rendered conducting

once each cycle of operation of the unit; means coupling the impulse point in the transfer tube operating circuit of each transfer tube to the input conductor of another unit to form an operative chain of the units so that the extinguishment of conduction in a transfer tube passes on an operation-inducing electric impulse to the next unit in the chain; an extinguishing tube for each transfer tube; and circuits connecting said extinguishing tubes to potential sources, to the associated transfer tubes, and to each other in a chain, so that, when conduction commences in the first extinguishing tube, the extinguishing tubes automatically become conducting serially one after another, extinguishing the associated transfer tubes in the same serial order if any be conducting.

13. A tens transfer device for a totalizer of the type which is made up of a plurality of cyclically operable denominational groups of tubes operable to accumulate amounts in response to impulses applied thereto and having an input conductor for each group of tubes, the combination of a transfer electron tube for each group; an operating potential supply circuit for each transfer tube including means which, when the transfer tube passes from a conducting state to a non-conducting state, gives rise to a positive potential impulse at an impulse point in the circuit; means connecting each transfer tube to its associated group to be controlled thereby so that the transfer tube is rendered conducting once each cycle of operation of the group; means coupling the impulse point in the transfer tube operating circuit of each transfer tube to the input conductor of another group to form an operative chain of the groups, so that the extinguishment of conduction in a transfer tube passes on an operation-inducing electric impulse to the next group in the chain of groups; an extinguishing electron tube for each transfer tube, each extinguishing tube having at least an anode and a cathode; means connecting each extinguishing tube to a source of anode-cathode potential, each of said connections including a resistance in the cathode circuit; means coupling the cathode of each extinguishing tube to the cathode of its associated transfer tube to pass an extinguishing impulse to the transfer tube each time the extinguishing tube becomes conducting; means connecting the extinguishing electron tubes in an operative chain wherein the condition of conduction in a tube of the extinguishing chain of tubes automatically renders the next tube conducting to cause the tubes to operate serially; and means coupled to the first tube of the extinguishing chain to start conduction in the first of the extinguishing tubes to initiate the sequential operation of the chain.

14. A tens transfer device for a totalizer of the type which is made up of a plurality of denominational rings of electron tubes operable to accumulate amounts in response to input impulses, there being an input means for each ring and in each ring a tube for zero and for each of the digits in the denomination, the combination of a transfer gaseous discharge electron tube for each ring, each transfer tube having at least an anode, a cathode, and a control member; means coupling the anode of the transfer tube of a denominational ring to the input means of the next higher denomination; means supplying each transfer tube with anode-cathode potential and a normally controlling control member potential, said means including a resistance in each

of the anode supply connections and resistance in the cathode supply connections; means coupling each transfer tube control member to the cathode of the zero tube of the associated denominational ring; a transfer control gaseous discharge electron tube for each transfer tube, each transfer control tube having at least an anode, a cathode, and a control member; circuit means supplying anode-cathode potential and normal controlling bias potential to the transfer control tubes, said circuit means enabling conduction in a transfer control tube to extinguish another previously conducting transfer control tube and including a resistance shunted by a capacitor in each cathode supply circuit; means coupling the cathode of each transfer control tube to the cathode of the associated transfer tube to enable conduction in a transfer control tube to extinguish a conducting transfer tube; means coupling the cathode of each transfer control tube with the transfer-tube control member associated with the next higher denomination to enable conduction in one tube to initiate conduction in the transfer control tube of next higher denomination; and means to temporarily remove the effective control bias on the transfer control tube control member associated with the lowest denomination, thus firing this transfer control tube to initiate the automatic firing of the control tubes one after another in sequence and thereby extinguishing any conducting transfer tubes in the same order to cause successive transfer of carry-over data.

15. In combination, a generator of electric impulses producing a fixed number of impulses in a cycle; a plurality of denominational output conductors; control means for selecting the number of impulses selected ones of the denominational output conductors receive from the impulse generator in a cycle of operation of the generator; a plurality of denominational banks of digit-representing electron tubes; means connecting the tubes of each bank in a circuit whereby they are rendered conducting one at a time in endless chain manner in response to electric impulses commonly received by the tubes of a bank; an electric impulse input means for each bank; a transfer tube for each bank; means connecting each transfer tube in a supply network to a potential source and to the associated bank so as to become conducting each time the associated bank makes a complete cycle of operation; means connecting supply network for a tube, at a point in the network having a potential rise when the tube changes from a conducting condition to a non-conducting condition, to the input means of another bank to form a series of banks; means to couple the impulse generator denominational output conductors to certain associated ones of the denominational bank input means for one or more cycles of operation of the impulse generator; and means controlled by the impulse generator and automatically operated between cycles of operation of the impulse generator to render all of the conducting transfer tubes non-conducting serially to accomplish successive transfers.

16. A generator of electric impulses which produces in one cycle of operation a number of impulses equal to the number of digits in a numerical denomination; a plurality of denominational output conductors; selectively operable means to connect any of the denominational output conductors to the impulse generator so that each conductor receives individually any selected number of impulses in a cycle of operation of the

generator up to the number of digits in the numerical denomination; a plurality of denominational representing banks of electron tubes, there being in each bank a tube representing each digit in the numerical denomination and also a zero tube, said banks being arranged according to denominational value; an input conductor for each bank of tubes; means connecting the tubes in a bank to a source of potential, to each other in an endless chain, and to the related input conductor so that, when a tube is rendered conducting, it causes every other tube in the bank to be rendered non-conducting and prepares the succeeding tube in the chain for operation so that an impulse on the input conductor renders the prepared tube in the chain conducting; means for coupling each generator denominational output conductor to an associated input conductor for one or more generator cycles; a transfer electron tube between each two banks; means connecting each transfer tube in a potential supply network having means thereon whereby, when any transfer tube changes from a conducting condition to a non-conducting condition, a positive impulse is produced at a point in its supply network; means coupling each transfer tube to the zero tube of the lower order associated bank so that, when the zero tube is rendered conducting, the associated transfer tube is rendered conducting; means connecting the banks into a totalizer by connecting the positive impulse point of a transfer tube network to the input conductor in the higher associated bank to form a denominational series; and means coupled to the transfer tube and controlled by the impulse generator to be operative following each cycle of the impulse generator and operating on each transfer tube in succession beginning with the first of the series to render any conducting transfer tube non-conducting to accomplish successive transfers from the lower to the higher denominations of the totalizer.

17. In combination, a plurality of denominational rings of electron tubes, each having a tube for every digit in the denomination including zero; an input conductor for each denominational ring; means connecting the tubes of a ring to operating potential sources, to each other, and to the related input conductor, so that the tubes in a ring are rendered conducting one at a time in sequence in response to electric impulses impressed on the associated input conductor; differential means to impress selected numbers of impulses on the input conductors in a cycle; transfer means coupling each two adjacent rings to form a totalizer, said transfer means each being conditioned, through said coupling, to the associated ring of lower denomination, when said ring passes through zero, so as to be later actuated to enter a unit of data, through said coupling, to the associated ring of higher denomination; transfer operating control means operable to actuate each transfer means in succession from the lower denomination of the totalizer toward the higher denominations, affecting the conditioned transfer means serially; means actuated by the differential means at the completion of its cycle of operation to start an operation of the transfer operating control means; and means actuated by the transfer operating control means at the completion of an operation thereof to initiate another cycle of operation of the differential means.

18. In a multiplying device, a plurality of electron tube counting rings each representing a nu-

merical denomination; transfer means coupling the rings into a totalizer; said transfer means being conditioned during entry of data into the rings to be responsive to a transfer signal to cause transfers to be made from a lower denomination to a higher denomination seriatim starting with the lowest denominational order; an impulse generator operable to issue selected numbers of electric impulses in a cycle of operation in selected denominations; means coupling said impulse generator to the counting rings to actuate them accordingly; means connected to the transfer means and operated by the impulse generator at the conclusion of a cycle of operation thereof to issue a transfer signal to cause an operation of the transfer means; and an impulse generator operating means coupled to the transfer means and to the impulse generator to cause the impulse generator to be operated at the conclusion of a transfer operation, said operating means being settable to be responsive a selected number of times.

19. In a multiplying device, the combination of a first group of electron tubes, there being one tube for each digit of a denominational order of a numerical system; means connecting the tubes in an operative chain and to power sources whereby they may be rendered conducting one at a time serially from a beginning conducting tube toward the end of the chain in response to electric impulses commonly received by all the tubes, a tube being rendered conducting for each impulse and extinguishing the preceding conducting tube and preparing a further tube for operation; a common input conductor coupled to the tubes to receive electric impulses; a common output conductor to which all the tubes are connected, which conductor receives an electric impulse as each tube becomes conducting; a plurality of denominational groups of digit-representing keys for setting up a multiplier factor; an energizing circuit for each denomination of keys, each of which circuits is switched, by an operated key of the denomination, to a tube, that number of tubes from the end of the chain corresponding to the value of the operated key, the energizing of a circuit causing conduction in the key selected tube; a stage control means operable in steps each caused by an electric impulse to energize each of the energizing circuits in turn; means to cause the stage control means to make its first step of operation to start a multiplication operation; means controlled by the chain of tubes and operated at the end of a chain of operations of the tubes, to create an electric impulse, said means coupled to the stage control means to impress the created impulse thereon to operate it a step; a second group of electron tubes equaling in number the number of digits in a denominational order of a numerical system; means connecting the tubes to each other in a chain and to power sources, so that, if the first tube is rendered conducting, all the tubes will be rendered conducting and extinguished serially, giving rise to a potential impulse for each tube rendered conducting, said serial operation forming a complete cycle; means coupling the output conductor of the first group of tubes to the first tube of the second group of tubes whereby an electric impulse on said output conductor causes conduction in said first tube of the second group; a plurality of denominational groups of digit-representing keys for setting up a multiplicand factor; an output conductor for said second group of tubes, which conductor has connection points therein representing the digits

and each point thereof receiving, of the impulses produced in a cycle of operation of the second group of tubes, a number of impulses equaling the value of the digit which it represents; a denominational output conductor for each denomination of multiplicand keys; and means operated by the keys for coupling the associated denominational output conductor to the connection points giving the number of impulses in a cycle corresponding to the value of said operated key.

20. A multiplier control unit for a multiplying device including a plurality of electron tubes equal in number to the digits of a numerical denomination; an input conductor; means connecting said tubes in an operative chain, to sources of potential, and to the input conductor so that they are rendered conducting one at a time in sequence in response to potential impulses impressed on said input conductor, said connections including means for producing an impulse each time any of the tubes becomes conducting; an output conductor to which all the digit tubes are coupled and which conductor receives an impulse each time a tube is rendered conducting; a plurality of denominational input conductors; a set of digit keys for each denominational input conductor; circuits controlled by said keys whereby each key, when operated, couples the associated denominational input conductor to a tube associated with the digit value of the key at a corresponding number of tubes distant from the end of the chain, whereby an electric impulse on a denominational input conductor causes conduction in the tube selected by operation of a key; a control tube; means connecting said control tube to a supply circuit, to the last tube of the chain and to the first-mentioned input conductor so as to be rendered conducting and extinguished on receipt of an impulse on said input conductor following conduction in the last digit tube of the chain, said conduction in the control tube also extinguishing the last digit tube of the chain; and a delay relay means coupled to the output conductor for relaying each output impulse after a pause.

21. The device of claim 20 wherein the electron tubes are gaseous discharge electron tubes of the grid controlled type.

22. The device of claim 20 wherein a zero key is provided with each denominational group of keys and wherein a circuit is provided for the control tube, which is controlled by the zero keys to couple the tubes selectively to the denominational conductors to cause it to become conducting on receipt of an electric impulse on its denominational input conductor whenever such zero key is operated.

23. The device of claim 20 including a control means for applying an electrical impulse on each denominational input conductor in turn, said control means being provided with a start means to apply an impulse to one of said denominational input conductors, and said control means being provided with other impulse-producing means operable in sequence and coupled to the other denominational input means and to said control tube to be operated thereby each time it becomes conducting, whereby the control means applies an impulse to another denominational input means each time the chain of tubes completes an operation.

24. The device of claim 1 in which a rectifier is included in the coupling between a transfer tube and the input conductor of the next higher denomination to prevent dissipation in the trans-

fer tube circuit of impulses emanating from the input source.

25. The device of claim 1 in which a rectifier is included between the input source and the input conductor at the point of coupling of the transfer tube of lower order to said input conductor to prevent dissipation of transfer impulses toward the input source.

26. The device of claim 1 in which timing elements are included in the chain connections between the extinguishing tubes to assure complete acceptance of a denominational transfer by a succeeding denomination before the transfer tube in the succeeding denomination is acted upon by the succeeding extinguishing tube.

27. A transfer device for a totalizer of the type which is made up of a plurality of cyclically operable denominational groups of tubes operable to accumulate amounts in response to impulses applied thereto and having an input conductor for each group of tubes, the combination of a transfer electron tube between each two denominational groups forming an ascending order of denominations; means coupling each of said transfer tubes to a source of power, to a tube in the lower one of the associated denominational groups, and to the input conductor of the next higher group whereby, if said tube in the lower group becomes conducting, the associated transfer tube becomes conducting and whereby, if a transfer tube is extinguished, it will pass on an electric impulse to the input conductor of the next higher denominational order; an extinguishing electron tube associated with each transfer tube; means coupling each of the extinguishing tubes to power sources through resistance and to its associated transfer tube so that, when conduction commences in the extinguishing tube, it extinguishes the associated transfer tube; means including capacitor timing elements coupling the extinguishing tubes in an operative ascending denominational order correlative to the rings so that, if the lowest order extinguishing tube is rendered conducting, and other extinguishing tubes will become conducting automatically seriatim in the chain sequence, there being a pause between conduction in the extinguishing tubes in the chain to allow for the carry-over of data between the rings; means to render the first extinguishing tube of the chain conducting; and an output means from the last extinguishing tube, which output means receives a positive potential impulse when said last tube becomes conducting.

28. The device of claim 27 wherein the coupling of the transfer tube to a source of power includes a switch which is opened in a resetting operation so that the tube of a denominational ring associated with the transfer tube may be caused to conduct without causing conduction in the associated transfer tube when the ring is reset to a beginning point.

29. The device of claim 27 wherein the extinguishing tubes are of the grid-controlled gaseous discharge type coupled in the chain cathode to grid.

30. In a multiplying device, in combination, a plurality of groups of electron tubes, there being in each group a tube for each digit of a denominational order of a numerical system; an input conductor for each group of tubes; means connecting the tubes of each group to power sources, to their common input, and to each other to form a ring so that, if a tube in a group is rendered conducting, it prepares the succeed-

ing tube so that an electric impulse on the input conductor renders the succeeding tube in the ring conducting and conduction beginning in said succeeding tube extinguishes the preceding conducting tube; a transfer electron tube between each two denominational groups forming an ascending order of denomination; means coupling each of said transfer tubes to a source of power, to a tube in the lower one of the associated denominational groups, and to the input conductor of the next higher group, said coupling between the transfer tube and the tube in the group enabling the transfer tube to be rendered conducting when said tube in the lower group becomes conducting, and said coupling between the transfer tube and the input conductor passing an electric impulse to the input conductor of the next higher denominational order when the transfer tube is extinguished; an extinguishing electron tube associated with each transfer tube; means coupling each of the extinguishing tubes to power sources and to its associated transfer tube so that, when conduction commences in the extinguishing tube, it extinguishes the associated transfer tube, said coupling to power sources enabling conduction in one extinguishing tube to extinguish another previously conducting extinguishing tube and said coupling to power sources including resistance; means including capacitor timing elements coupling the extinguishing tubes in a chain operative according to ascending denominational orders so that, when the lowest order extinguishing tube is rendered conducting, it will initiate the sequence of operation of the extinguishing tubes which will become conducting automatically seriatim in the chain sequence, there being a pause between conduction in the extinguishing tubes in the chain to allow for the carry-over of data between the rings; means to render the first extinguishing tube of the chain conducting; an output means coupled to the last extinguishing tube of the chain, which output means receives a positive potential impulse when said last tube becomes conducting; selective means for setting up a multiplicand factor, said means including a plurality of denominational rows of digit keys; a denominational output conductor for each row of keys; a generator of electric impulses operable in cycles to produce in each cycle a number of electric impulses equal to the number of digits in a denomination; a terminal point for each digit in a denominational order; means coupling the terminal points to the impulse generator and directing said produced impulses to one or more digit-representing terminal points so that each point receives in a cycle that number of impulses representing the value of associated digit; switch means operated by each digit key, a key, when operated, through said switch connecting the terminal point of corresponding value to the associated denominational output conductor; cycle-initiating means operable to cause the impulse generator to have a cycle of operation; a denominational distributor device for relaying and routing the impulses issuing on the denominational output conductors to appropriate orders of the denominational rings, said distributor device being controllable for denominational shifts according to the stages of a multiplying operation; a plurality of denominational rows of digit-representing keys operable for setting up a multiplier factor; a plurality of electron tubes, there being one for each digit of a denomination, said tubes being associated with the multiplier keys;

a multiplier input conductor; a multiplier output conductor; means connecting the multiplier tubes serially in an operative chain, to power sources, to a multiplier input conductor, and to a multiplier output conductor, so that, if a multiplier tube is rendered conducting, it creates an electric impulse on the multiplier output conductor, primes the tube succeeding it in the chain to be responsive to an electric impulse on the multiplier input conductor by becoming conducting, and extinguishes any other conducting multiplier tube; a plurality of multiplier stage initiating energizing conductors, there being one associated with each denominational row of multiplier keys; a switch for each multiplier key, the operation of a key coupling, through its related switch, the associated stage initiating energizing conductor to the associated tube so that an electric impulse on such a conductor will cause the multiplier tube coupled thereto by a key-operated switch to conduct; means coupling the multiplier output conductor to the impulse generator cycle initiating means whereby, if one of the multiplier tubes commences to conduct, it will cause a cycle of operation of the impulse generator to occur; means coupling the output means from the last extinguishing tube to the multiplier input conductor so that the act of conduction occurring in the last extinguishing tube will cause conduction to occur in that multiplier tube next in the chain to a conducting tube thereof; a stage control means including a start means, said stage control means being operable in steps each caused by an electric impulse, to energize each of the stage energizing conductors in turn, by causing an electric impulse therein; means coupled to the last multiplier tube in the chain and actuated by receipt of an impulse on the multiplier input conductor when the last multiplier tube is conducting to produce an electric impulse to step the stage control means; means coupling the stage control means and the denominational distributor to control it to route the product impulses according to the active stage of the stage control means; and means coupling the means to render the first extinguishing tube conducting to the impulse generator to be actuated thereby at the conclusion of a cycle of operation of the impulse generator to create an electric impulse which is impressed on the first extinguishing tube to cause it to conduct, initiating a transfer cycle.

31. The device of claim 30 in which the denominational distributor includes a plurality of electron tube relays arranged in columns representing the multiplying stages and in rows representing the impulse generator output conductors, includes circuits connecting said tubes in a column to the stage control means to be primed by the activeness in the associated stage of the stage control means so as to be responsive to relay impulses on the associated one of the impulse generator denominational output conductors, and includes means connecting said tubes in each diagonal across the columns and rows to a common output conductor which is in turn coupled to the input conductor of an associated ring of tubes in the totalizer representing such product data.

32. The device of claim 30 in which the stage control means includes an impulse-producing control electron tube for each multiplying stage, includes circuits coupling said tubes together, to power sources, to the denominational distributor and to the multiplier energizing conductors so

as to become conducting in sequence, first in response to an operation of the start means and thereafter in response to the impulses from the stepping means, said tubes each when conducting being operable through the coupling between the stage control and denominational distributor to prime the associated stage of the denominational distributor and when commencing to conduct giving rise to an energizing impulse to cause the selected one of the multiplier tubes in the associated stage to become conducting.

33. The device in claim 30 wherein all the electron tubes are of the gaseous discharge type having at least an anode, a cathode, and a control element.

34. The device in claim 30 wherein the coupling made between the multiplier stage initiating conductors and the tubes by the operated multiplier keys is such that the multiplier tube made to conduct by reason of an energizing electric impulse being switched thereto by an operated key is that number of tubes from the end of the chain as represents the digit value of the operated key.

35. The device of claim 30 in which the stage stepping control means is a gaseous discharge electron tube connected to power sources, to the last multiplier tube in the chain, to the multiplier input conductor, and to the stage control means so that, upon receipt of an electric impulse on the multiplier input conductor when the last tube of the chain is conducting, the said electron tube will commence conducting and then self-extinguish, passing on an electric impulse to said stage control means to operate it a step.

36. In a calculating machine, a cyclically operable producer of electric impulses, producing in each cycle a number of impulses equal to the number of significant digits in a denomination

40 of a numerical notation; means operable to initiate a cycle of operation of the impulse producer; transfer-initiating means operated by the impulse producer at the conclusion of a cycle of operation thereof; a digit-representing output circuit for each digit of a denomination, each circuit connected to the impulse producer so as to receive in one cycle of operation of the impulse producer a number of the produced impulses equal to the value of the digit which it represents, a produced impulse being received on all of the affected digit-representing output circuits at the same time; a plurality of denominational output circuits, each of which may be connected to one of the digit-representing output circuits

55 for one or more cycles of operation of the impulse producer; entry receiving means for selectively connecting the proper digit-representing output circuits to the denominational output circuits according to one factor of a multiplication;

60 a denominational totalizer including denominational elements actuatable by electric impulses and transfer elements, and including circuits coupling said transfer elements to their associated denominational elements to be conditioned for operation when the associated denominational elements pass through zero; routing means for selectively coupling the denominational output circuits to those denominational elements of the totalizer associated with the various stages of a multiplying operation; means coupled to the transfer elements and cyclically operable for serially operating the conditioned transfer elements, starting with the lowest denominational order, to accomplish accrued carry-

75 overs successively; means connecting the trans-

fer-initiating means to the transfer-operating means whereby, at the conclusion of an operation of the impulse producer, the transfer-initiating means causes a cycle of operation of the transfer operating means; and means selectively controlled according to the other factor of a multiplication and connecting the transfer operating means to the routing means and to the impulse producer initiating means whereby the impulse producer is caused to have a cycle of operation after each transfer-operating cycle in each of selected stages for a selected number of times, thus causing the entry into the totalizer of the selected impulse data a selected number of times for each multiplying stage.

37. In a multiplying machine, the combination of a totalizer including denominational devices each actuatable by unit-representing electric impulses and including transfer means operable between data-entering periods to accomplish denominational carry-overs between the devices, said totalizer thus being able to accept data in one or more denominations simultaneously; an electric impulse producer cyclically operable to produce a plurality of electrical impulses in a cycle and including means to thereafter initiate an operation of the transfer means; means operable by the transfer means to produce a signal after each operation of the transfer means; a plurality of denominational representing output circuits; factor entry receiving means for selectively connecting the denominational representing output circuits to the impulse producer so that they receive in a cycle of operation of the impulse producer a number of impulses equalling the corresponding denominational digit of one of two multiplication factors; a denominational distributor selectively operable for coupling the output conductors to the proper totalizer denominational devices in stages corresponding to the digits of another multiplication factor; and means operable in response to each of said signals and containing means settable according to said other factor to cause the cycling of the impulse generator a number of times corresponding to each digit value of said other factor and, in addition, containing means to control the denominational distributor to cause the proper stage of the denominational distributor to be effective for any given cycle of the impulse generator.

38. In a multiplying device, in combination, a product-receiving device including denominational data-receiving elements formed into a totalizer by transfer elements coupling adjacent denominations, said product-receiving device being operable in a data-entering cycle followed by a transfer cycle; cyclically operable means for entering data into selected denominations of said totalizer simultaneously; transfer operating means cooperable with the transfer elements and operable in a transfer cycle to cause the transfer elements to effect necessary transfer entries; means actuated by the cyclically operable means automatically at the conclusion of each data-entering cycle to initiate an operation of the transfer operating means; and operation-initiating means for said data-entering means operated by the transfer operating means automatically at the conclusion of a transfer cycle to initiate a further data-entering cycle of the data-entering means.

39. In a multiplying device, in combination, a product-receiving device including denominational data-receiving elements formed into a

totalizer by transfer means coupling adjacent denominations to accomplish carry-overs, said product-receiving device being operable in a data-entering cycle followed by a transfer cycle; cyclically operable means for entering a multiplicand factor into the pertinent denominations of product-receiving elements simultaneously;

5 means operated by the multiplicand-entering means at the conclusion of a cycle thereof to initiate a cycle of operation of the transfer means; said transfer means producing a control electric impulse at the conclusion of a transfer cycle; a multiplier unit coupled to said transfer means and settable to be responsive to a selected number of said control electric impulses, and including means operable at each response to generate a further control impulse; and means coupling the multiplier unit to the multiplicand unit to enable each of said further control impulses to initiate a cycle of operation of the multiplicand-entering means.

10 40. In combination, a totalizer including a series of cyclically operable denominational elements arranged according to powers, an associated transfer element for each denominational element, and means coupling the transfer elements to adjacent denominational elements, said transfer elements being prepared, through the coupling to their associated denominational elements, when the associated denominational element completes a cycle of operation, for a transfer operation to enter a unit in the next denominational element; cyclically operable differential means to actuate the denominational elements 15 to enter selected amounts therein; transfer control means coupled to the transfer elements and actuatable to affect the transfer elements serially from the lowest order to the highest order to effectuate a transfer by the prepared transfer elements; means operated by the differential means at the conclusion of a cycle of operation to initiate an operation of the transfer control means; and means actuated by the transfer control means, at the conclusion of its operation, to 20 cause another cycle of operation of the differential means.

25 41. In a multiplying machine, the combination of a totalizer including a cyclically operable denominational carry-over transfer device having a starting means and means to issue an end-of-cycle signal when a transfer cycle is completed; a cyclically operable multiplicand-entering device operable to enter a multiplicand factor into the totalizer in a cycle of operation and including 30 means to operate the starting means of the transfer device at the end of the cycle of operation; a multiplier means controlled by the transfer device, operable in steps, each step being initiated by the end-of-cycle signal of the transfer device; and means coupled to the multiplicand-entering device and operated by the multiplier means each time it makes a step of operation, for cycling the multiplicand-entering device.

35 42. A tens transfer device for a totalizer of the type which consists of a plurality of denominational elements arranged in a series of ascending orders and capable of receiving simultaneous entries in various orders, each of said elements being cyclically operable in digit-representing unit steps through a zero position, the combination 40 of a transfer means between each order and the next higher order; means connecting said transfer means to its associated lower order to be conditioned thereby for a transfer opera-

35

tion during an entry if the associated lower order denominational element passes to or through zero; means connecting the transfer means to the next higher order to enable a transfer entry to be made therein if the transfer means has been conditioned by the associated lower order and is thereafter operated to perform a transfer operation; an electron tube actuator connected to each transfer means, the condition of conduction in a tube causing the associated transfer means to be actuated to perform a transfer operation if it is conditioned and thereby enables the transfer means to pass on a unit of data to the next higher denominational element; and means interconnecting the tubes so that they will become conducting serially from the lowest order with a pause between the operation of the tubes to permit a transfer entry to condition the next higher order transfer means if said transfer entry causes the said next higher order denomination to pass to or through zero.

43. A tens transfer device for a totalizer of the type which is made up of a plurality of denominational elements arranged in a series of ascending orders and capable of receiving digit entries simultaneously in various orders, each of said elements being cyclically operable in digit-representing unit steps through a zero position, the combination of a transfer means between each order and the next higher order; means connecting each of said transfer means to its associated lower order to be conditioned thereby for a transfer operation if the associated lower order denominational element passes to or through zero during an entry therein; means connecting the transfer means to the next higher order to enable a transfer entry to be made therein if the transfer means has been conditioned by the associated lower order and is thereafter operated to perform a transfer operation; an electron tube actuator including a tube connected to each transfer means, the condition of conduction in a tube causing the associated transfer means to be actuated to perform a transfer operation if conditioned and thereby enables the transfer means to pass on a unit of data to the next higher denominational element; and means interconnecting the tubes so that they will become conducting serially automatically beginning with the lowest order, said interconnections including a capacitor for delaying action between tubes of the series to provide a pause between the operation of the tubes to permit a transfer entry to condition the next higher order transfer means if said transfer entry causes the said next higher order denomination to pass to or through zero.

44. A transfer device for a totalizer of the type which is made up of a plurality of denominational elements arranged in a series of ascending orders and capable of receiving digit entries simultaneously in various orders, each of said elements being cyclically operable in digit-representing unit steps through a zero position, the combination of a transfer means between each lower order and the next higher order; means connecting each of said transfer means to its associated lower order to be conditioned thereby for a transfer operation if the associated lower order denominational element passes to or through zero during an entry therein; means connecting the transfer means to the next higher order to enable a transfer entry to be made therein if the transfer means has been conditioned by the associated lower order and thereafter performs a transfer operation; an electron

36

tube associated with each transfer means; means connecting each tube with the associated transfer means and to electric potential sources, so that, if a tube conducts, it can cause the associated transfer means, if conditioned, to pass on a unit of data to the next higher denominational element; means normally holding each tube in a non-conducting condition; means connecting a lower order tube to the next higher order tube, said connections including a timing capacitor and said connections causing a tube of higher order to be rendered conducting automatically by reason of conduction in the next lower tube after a pause determined by the capacitor; and means to initiate conduction in the tube of the lowest order, resulting in the actuation of all conditioned transfer means serially and timed by the capacitors to permit the effect of a transfer on a higher order to condition the higher order transfer means before it is actuated.

45. A cycle control means for a multiplying device including the combination of a group of electron tubes, there being in the group one tube for each digit of a denominational order of a numerical system; means connecting the tubes in an operative chain and to power sources whereby they may be rendered conducting one at a time serially from a selected beginning conducting tube toward the end of the chain in response to electric impulses commonly received by all the tubes, the connections enabling conduction in a tube to render the tube following it responsive to the next impulse and enabling conduction in said following tube, which is brought about by the next impulse, to extinguish the previously conducting tube; a common input conductor coupled to all of the tubes to receive electric impulses; a common output conductor to which all the tubes are connected, which conductor receives an electric impulse as each tube becomes conducting; a plurality of denominational groups of digit-representing keys for setting up a multi-digit number; an energizing circuit for each denomination of keys; means whereby each of said circuits is switched by an operated key of the denomination to a tube, that number of tubes from the end of the chain corresponding to the value of the operated key, the energization of a circuit causing conduction in the key-selected tube; a control means, operable in steps in response to electric impulses, to energize the energizing circuits in turn; means to cause the first step of operation of the control means to thereby energize the first energizing circuit; and means controlled by the chain of tubes and operated at the end of a chain of operations of the tubes, to create an electric impulse, said means coupled to the control means to impress the created impulse thereon to operate it an additional step on receipt of such impulse.

46. The device of claim 27 wherein the transfer tubes are of the gaseous discharge type having at least an anode, a cathode, and a control element, wherein the coupling of the transfer tube to a tube in the lower one of the associated groups consists in a connection between the control element of the transfer tube and the cathode of the associated tube in the ring of lower order, wherein in the coupling between the transfer tube and the input conductor of the next higher group consists in a coupling between the anode of the transfer tube and the input conductor of the associated ring of higher order, and wherein the coupling of the tubes to a source of power in-

cludes a high resistance in its anode supply circuit for each tube.

47. The device of claim 27 wherein the coupling of the transfer tubes to a source of power includes a control potential normally blocking operation of the tube and wherein the coupling to the tube in the lower one of associated denominations enables the control potential to be reduced temporarily to the conduction point by the commencement of conduction in the associated tube of the lower denomination.

48. The device of claim 27 wherein there is provided a switch in the coupling of the transfer tube to power sources to enable the operating potential to be removed to incapacitate each transfer tube, and means including a switch for the tube in each ring which is coupled with a transfer tube to supply firing potential to the control element thereof when the last-mentioned switch is closed while the associated transfer tube is incapacitated.

49. The device of claim 30 wherein the impulse generator includes an electron tube for each digit of a denomination, each of said tubes having at least an anode, a cathode, and a control element, includes connections for coupling said tubes cathodes to control element in an operative chain for automatic sequential operation and includes connections for coupling the tubes to power sources, each cathode being coupled through resistance to power sources, and all anodes being coupled to a common potential source, said connections being effective upon the rendering of the first tube of the chain conducting to cause them to become conducting and extinguished automatically in succession in the chain, whereby, at each cathode, an electric impulse is pro-

duced upon its tube becoming conducting, and wherein means directing the produced impulses to the terminal points includes connections connecting each point to an associated tube and to each other in a network through rectifiers all oriented to pass current in the same direction.

50. The device of claim 30 wherein the impulse generator cycle initiating means includes two relay electron tubes and means coupling them in tandem to pass on an electric impulse from the multiplier output conductor to the impulse generating means after a pause to permit stabilization of potentials in the system after a previous data-entering cycle.
